UNITED STATES PATENT OFFICE.

JOSEPH A. WILKINSON, OF HIAWATHA, KANSAS.

MACHINE FOR SHELLING CORN.

No. 870,919.

Specification of Letters Patent.

Patented Nov. 12, 1907.

Application filed June 12, 1907. Serial No. 378,470.

To all whom it may concern:

Be it known that I, JOSEPH A. WILKINSON, a citizen of the United States, resident of Hiawatha, in the county of Brown and State of Kansas, have made a certain new and useful Invention in Machines for Shelling Corn; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side elevation of the invention. Fig. 2 is a section on the line 2—2, Fig. 3. Fig. 3 is a section on the line 3—3, Fig. 2. Fig. 4 is a perspective view of the supporting frame.

The invention relates to corn shelling machines, having for its object the provision of improved means of durable and efficient character for the purpose.

20 The invention consists in the novel construction and combination of parts as hereinafter set forth.

In the accompanying drawings, illustrating the invention the letter *a*, designates a supporting frame, shown in the present case as made from a single piece of bar metal, doubled at one end as at *a'*, and having upward extending branches *b*, lying close together for a portion of their length one of such branches being bent laterally away from the other branch *b*, (which is vertical throughout its length), and then bent vertically again to form forked or bifurcated portions *c*, which are provided with journal bearings for the reception of the rotatable operating shaft *d*, of the machine.

Secured to one end of the shaft *d*, at the smaller 35 closed end thereof, is the shelling cone *e*. The converging side walls of this cone are provided with radial slots *f*, four being shown, such side walls having radial outward extensions or wings *g*, secured thereto in any suitable manner, or formed thereon by casting. The 40 slots *f*, are located intermediately of the ends of the cone and extend a substantial part of the length thereof.

The radial shelling blades *h*, which engage the radial slots, are of broad character, having outward extending portions *h'*, pivoted to the radial wing extensions *g*, of the cone at their rear ends at *g'*, and inward extending portions *h''*, projecting into the interior of the cone.

50 In order to adapt the device for operation upon ears of corn of varying sizes, the pivoted shelling blades are made of yielding character, each blade having at its forward end connection with a bolt *j*, which passes

through an aperture of a laterally projecting lug *j'*, of the radial wing extension *g*, a coiled spring *k*, being located upon the bolt between such laterally projecting lug and a lug *k'* of the shelling blade. A nut *k''* upon this bolt serves for adjustment of the blade *p*, and of the tension of the spring *k*. The operating or inner edges of the shelling blades have a converging relation to each other and are curved outward at their end portions at *i*, to facilitate the entrance of the ear of corn. The opposite or inner end portion of each blade is similarly curved, as shown at *i'*.

In use the shelling blades are subject to considerable strain and are liable to be broken off. In the present 65 case these blades are braced intermediately of their width throughout their length against the side walls of the radial slots of the cone. In this way, the securing connection of the shelling blades with the outward extending wings of the cone is relieved of strain, whereby a durable connection is obtained. A comparatively light, inexpensive, and yet durable and effective machine is the result. The operating shaft of the machine is provided with a suitable crank handle at its free or outer end, as shown at *l*. The machine is designed to be secured to a suitable upright support by bolts passing through perforations of lateral integral extensions *a''*, at the bottom of the branches *a'*. In case the shelling blades become worn, they may be removed, and replaced by new blades.

Having thus described the invention, what I claim and desire to secure by Letters Patent is—

1. A machine for shelling corn, having a rotatable shaft, a hollow shelling cone, closed at its smaller end, which has connection with said shaft, the side walls of said cone having radial slots, radial wing projections at one side of said slots secured to the cone, shelling blades fitting in said slots having outward extending portions secured to said wing projections and inward extending portions for action upon the corn, and a supporting frame formed of an integral piece of metal having a doubling bend at its bottom, and upward extending branches lying close together, one of said branches having a laterally bent portion provided with an upward bend to provide separated journal bearings for said shaft, one of said branches having integral lateral 85 perforated projections at its lower end.

2. A machine for shelling corn having a rotatable shaft, a hollow shelling cone secured thereto at one end, the side walls of such cone being provided with radial slots located intermediately of the ends of the cone and extending a substantial part of the length thereof, radial wing projections carried by the cone at one side of such slots, shelling blades fitting in such slots and having outer portions extending beyond the cone, pivoted at their rear ends to said wing projections, and having a yieldable connection at their forward ends with the wing projections.

3. A machine for shelling corn having a rotatable shaft, a hollow shelling cone secured at one end thereto, the side walls of such cone being provided with radial slots located

intermediately of the ends of the cone and extending a substantial part of the length thereof, radial wing projections carried by the cone at one side of such slots, such wing projections having each a laterally projecting lug at its forward end provided with an aperture, shelling blades fitting in said slots, having outer portions extending beyond the cone pivoted at their rear ends to said wing projections and having at their forward ends laterally projecting lugs, bolts carried by the lugs of said blades and

having sliding engagement with the apertures of the lugs 10 of said wing projections, and coiled springs upon said bolts.

In testimony whereof I affix my signature, in presence of two witnesses.

JOSEPH A. WILKINSON.
